[57] ABSTRACT

A device for supporting dentures or the like for cleaning purposes including a support member having a seat-like abutment construction at one end, and a gripping member attached to the support member having a plurality of flexible projections extending outwardly therefrom adapted for supporting a denture thereon and coacting with the seat-like abutment construction for holding the denture against movement during cleaning thereof.

DENTURE SUPPORT DEVICE**BACKGROUND OF THE INVENTION**

This invention relates to a device, and more particularly relates to an improved construction of a denture device which can be employed for supporting and/or holding dentures so that they may be thoroughly cleaned and/or stored when not in use.

Heretofore, it has been a problem to provide a reliable and sanitary method for cleaning and/or storing dentures. This is an especially acute problem because of the relatively fragile nature of the permanent resin materials from which dentures are generally fabricated. Accordingly, there has not been provided a satisfactory method for cleaning dentures so as to prevent damage or injury thereto while maintaining a sanitary condition during cleaning thereof. One such method has been to provide a relatively complex cleaning device including a casing for mounting upper and lower dentures in conjunction with an articulated brush for cleaning the same. With regard to a typical prior art device, reference may be had to U.S. Pat. No. 3,230,572.

SUMMARY OF THE INVENTION

A device for supporting dentures or the like comprising a support member, a gripping member attached to said support member, said gripping member including a plurality of flexible projections extending outwardly from said gripping member adapted to receive in supporting relation a denture thereon, and said support member including a seat-like abutment construction coacting with said gripping member adapted for holding said denture against movement during cleaning thereof. In one form, a base member is attached to said support member on the side opposite said gripping member to provide a support for said device.

From the foregoing and subsequent description taken in conjunction with the accompanying drawings, it will be seen that the present invention provides a novel construction for a denture device which is of a simple, yet rugged construction and which is economically feasible to produce and maintain. The device is constructed and arranged so as to hold the denture firmly against movement so as to prevent damage or injury thereto during the cleaning operation while maintaining the same in a relatively sanitary condition. The device lends considerable flexibility to the cleaning operation since the denture to be cleaned is supported in a manner so as to be accessible from a plurality of positions without interference from auxiliary and/or component parts. In addition, the device is of a lightweight construction which can be easily stored and which itself can be readily cleaned for repeated usage.

BRIEF DESCRIPTION OF THE DRAWINGS

FIG. 1 is a generally perspective view of the denture device made in accordance with the present invention;

FIG. 2 is a side elevation view, on a reduced scale, of the denture device made in accordance with the present invention;

FIG. 3 is a front elevation view looking generally from the right-hand side of FIG. 2; and

FIG. 4 is an enlarged fragmentary section view taken along the line 4-4 of FIG. 3.

DESCRIPTION OF THE PREFERRED EMBODIMENTS

Referring again to the drawings, and to FIG. 1 thereof, there is illustrated the denture device, designated generally at 2, for supporting dentures or the like (not shown) for purposes of cleaning and/or storing the same. In the form shown, the device 2 generally includes a base member 4, a support member 10 mounted on said base and a gripping member 28 disposed on said support member 10 for mounting a denture thereon, as will hereinafter be more fully described.

As shown, the base member 4 is of a relatively thin plate-like construction which may be made of a flexible, washable material to provide an adequate supporting surface for the device. Preferably, the base member 4 is made from an elastomeric material, such as rubber or from a suitable plastic material, as desired. The base member 4 is generally of an oblate configuration, in top plan view, defined by a curved outer peripheral surface 6 which merges at opposed sides into a generally planar rear surface 8. Moreover, the curved peripheral surface 6 and the planar or rectilinear surface 8 conjointly provide a generally horseshoe-like configuration, in top plan view.

The supporting member 10 may be attached to the upper flat surface 7 of the base member 4 so as to be generally centrally disposed with respect thereto. The support member 10 may be fixedly attached to the base member 4 by any suitable means, such as by means of an adhesive or by molding techniques as known in the art. In the form shown, the support member 10 has a generally L-shaped configuration in side elevation (FIG. 2) defined by a seat-like member 12 and an upstanding back member 14 which extends generally perpendicular with respect to the general plane of the base member 4. The back member 14 is generally of the shape of a rectangular prism defined by a flat rear surface 15, a flat front surface 17 and a flat upper surface 18, as best seen in FIG. 4. The seat member 12 has an inclined upper surface 19 (FIG. 2) which extends outwardly and upwardly in direction away from the back member 14, and merges with the front surface 17 in a rounded curvature or radius, as at 16, so as to provide a trough-like construction at the juncture therebetween so as to discharge fluid materials and the like in a direction from the front toward the rear of the device. Accordingly, by this arrangement, the back member 14 provides an abutment and back-wash arrangement against which the dentures or the like may be disposed for cleaning by manual brushing or the like.

As shown, the seat member 12 has a curved front peripheral surface 20 which corresponds generally to the curved peripheral shape of the surface 6 of the base member 4. As best seen in FIG. 1, the seat member 12 has a pair of oppositely disposed side walls 21 which merge with the curved front surface 20 so as to define a pair of oppositely disposed shoulders, as at 22, which may be disposed slightly forward of the geometric center of the base member 4. In the form shown, the side walls 21 may extend generally parallel to one another or may taper toward one another in a direction toward the back member 14 so as to gradually merge with the rear surface 15 thereof. In the invention, the supporting member 10 is preferably made from a flexible material. Preferably, the material is a relatively low-density,

high-quality material, such as elastomeric or polymeric materials. For example, it has been found that foam rubber or sponge plastic, such as flexible urethane foams, produce satisfactory results. By this arrangement, the supporting member 10 provides a cushion-like construction for supporting the dentures, and which may be compressed upon application of force to the dentures during cleaning thereof. This provides a high stability construction and enables the dentures to be adequately, but yieldably supported so as to provide access thereto from multiple angles for optimum cleaning during cleaning, such as by brushing or the like. Moreover, this material is of a cellular construction having the ability to absorb and hold fluids, such as water, cleaning fluids or the like, to facilitate the cleaning operation, yet which can be easily compressed for cleaning and/or rinsing of the device itself.

In the invention, the gripping member 28 is fixedly secured to the upper surface 19 of the support member 10, such as by means of a suitable adhesive or molding technique as are known in the art. As shown, the gripping member has a generally plate-like body 30 of flat construction from which extends a plurality of projections 32. In the embodiment illustrated, the projections 32 are of a pointed construction and are generally symmetrically spaced with respect to the member 30. The projections 32 are substantially of equal length so that the outer terminal ends thereof define a inclined plane extending generally parallel to the upper surface 19 of the seat member 12. As shown, the gripping member has a curved front surface 33 (FIG. 2) which is in a form of a partial ellipse corresponding in configuration to the front surface 20 of the support member 10. The rearward portion of the gripping member is defined by a generally semi-circular surface 34 which merges with the front surface 33 to define shoulders, as at 31, which are disposed in the general vertical plane of the corresponding shoulders 22 provided in the seat member 12.

In the embodiment illustrated, the gripping member 28 and corresponding projections 32 are preferably made of a flexible, high strength material having good coefficient of friction characteristics for gripping and holding dentures in a relatively stationary position during cleaning thereof. Preferably, such member is made from rubber. By this arrangement, the dentures may be supported in gripped relation on the projections 32 and oriented for bearing engagement against the flexible back wall 14 to provide a nesting coaction therewith. Moreover, the gripping member is flexible, but has greater rigidity than the support member 10 so that the latter may be compressed upon application of pressure, such as a force applied to the dentures during cleaning thereof. This enables the dentures to be grippingly, yet yieldably supported during the cleaning operation, such as by manual brushing or the like, thereby to provide optimum accessibility to the same while being cleaned.

In the invention, the projections 32 may be of any shape, but are preferably of a conical configuration having a height less than the height of the back member 14. Similarly, the projections may be arranged in any suitable pattern, but good results have been provided by arranging the projections in linear rows with each row being disposed in staggered or offset relation with respect to an adjacent row, as best seen in FIG. 4.

In general, the device may be made from many different types of material correlated for the desired pur-

pose. For example, in the present invention, the support member 4 and the gripping member 28 may be made of the same type of material, such as rubber, while the support member 10 is made from a flexible material, such as foam rubber or urethane foam. Accordingly, it is important that the gripping member have sufficient coefficient of friction and flexibility characteristics for holding the dentures while the support member incorporates flexibility characteristics to enable the same to be compressed in a direction toward the base member 4 in order to provide the optimum angular orientation of the dentures during cleaning thereof, as aforesaid.

I claim:

1. A device for supporting a denture or the like for cleaning comprising,
a support member,
said support member includes an upper base surface and an upwardly extending back wall projecting upwardly from one end of said upper base surface defining a generally L-shaped configuration in side elevation,
a gripping member mounted on said upper base surface,
said gripping member including a generally flat body attached to said upper base surface and having a plurality of projections projecting upwardly from said body for engagement with said dentures when disposed on said gripping member to prevent lateral shifting movement with respect to said device, said projections disposed in generally symmetrical, laterally-spaced relation with respect to one another and have a length which is less than the height of said back wall such that the dentures can be oriented in any position while in abutting engagement with said back wall to support such during cleaning thereof,
said gripping member being made of an elastomeric material,
said support member being made of a flexible, polymeric material having a cellular construction such that the dentures are yieldably supported to provide access from multiple angles for optimum cleaning thereof and to enable absorption of fluids and compression of said support member for cleaning and/or rinsing of the device.

2. A device in accordance with claim 1, wherein said support member includes an upper base surface disposed at an angle with respect to said back wall so that the support member defines a generally L-shaped configuration in side elevation.

3. A denture device in accordance with claim 1, wherein said support member and said gripping member are angularly disposed relative to said seat-like abutment construction.

4. A device in accordance with claim 1, wherein said support member is made from a flexible, polymeric material, and wherein
said gripping member is made from an elastomeric material.

5. A device in accordance with claim 1, including a base member attached to said support member on the side opposite said gripping member, said base member having a greater peripheral surface area as compared to the peripheral surface area of said support member.

6. A device for supporting a denture or the like, comprising
 a support member,
 a gripping member attached to one side of said support member,
 said gripping member includes a plurality of projections extending outwardly from said gripping member adapted to receive in supporting relation a denture thereon,
 said support member includes an upwardly extending back wall projecting above and beyond the general plane of said gripping member for abuttingly engaging a denture when supported on said gripping member,
 said support member includes an upwardly extending back wall projecting above and beyond the general plane of said gripping member for abuttingly engaging a denture when supported on said gripping member,
 said projections are disposed in generally symmetrical, laterally-spaced relation with respect to one another and have a length less than the height of the said back wall such that said denture may be oriented in any direction and in any abutting position against the back wall during cleaning of said denture, and
 said support member includes a pair of tapered side walls disposed in converging relation in a direction toward said back wall at one end thereof, and includes a curved front wall at the opposite end merging with said side walls between said ends thereof.
 7. A device in accordance with claim 6, wherein said gripping member has a curved front wall disposed generally complementary to the front wall of

said support member, and the respective junctures of the curved front walls of said support and gripping members defining a pair of oppositely disposed shoulder portions spaced laterally of said back wall.

8. A device in accordance with claim 1, wherein said upper base surface extends angularly, upwardly and outwardly in a direction away from said back wall.

9. A device for supporting a denture or the like for

cleaning, comprising

a yieldable, cellular support member,
 said support member includes an upper base surface and an upwardly extending back wall projecting upwardly from one end of said upper base surface, an elastomeric gripping member mounted on said upper base surface,
 said gripping member including a generally flat body attached to said upper base surface and having a plurality of projections projecting upwardly from said body for engagement with said denture when disposed on said gripping member to prevent lateral shifting movement with respect to said device, and

said projections disposed in laterally-spaced relation with respect to one another and having a length which is less than the height of said back wall such that the denture can be oriented in any position while in abutting engagement with said back wall to support such during cleaning thereof.
